Inventor
Oscar Byron,
By *Peterson, Vaughan & Co.*
Attorney

UNITED STATES PATENT OFFICE.

OSCAR BYRON, OF JERSEY CITY, NEW JERSEY.

SOUND-RECEIVER EARPIECE.

Application filed August 3, 1922. Serial No. 579,437.

To all whom it may concern:

Be it known that I, OSCAR BYRON, a citizen of the United States, and residing at 507 Summit Avenue, Jersey City, in the 5 county of Hudson and State of New Jersey, have invented certain new and useful Improvements in Sound-Receiver Earpieces, of which the following is a clear and exact specification, reference being had to the accompanying drawing, which forms a part of this specification.

This invention relates to ear contacting members for use with sound receivers, such for example as those employed with the head 15 piece of telephone instruments and the receiving sets for radio broadcasters, and my improvement is directed particularly to an ear contacting member which is capable of application directly to the ear of the user in a 20 manner to exclude all external noise and vibration; also to enable the device to be applied and worn with a maximum of comfort.

With the head pieces of receiving sets 25 now in use either low efficiency in external sound exclusion exists or else the pressure exerted to provide snugly ear enclosing means, whether applied to the ear or to the head around the ear, involves considerable 30 discomfort through protracted usage; and it is an object of my invention to provide means for the remedy of this condition.

Therefore my invention consists in the use of a pad of soft, resilient material such 35 as spongy rubber, which can be applied contactingly against the ear under moderate pressure, so as to mould or embed the irregular contour of the ear into the substance of the pad; and in providing the pad with 40 an orifice therethrough, for communication with the auditory canal of the ear.

The pad may be suitably connected to a sound receiver, and in one form of my invention it is provided with means whereby 45 it is capable of removable engagement with a receiver.

Other features and advantages of my invention will hereinafter appear.

In the drawing:—

50 Figure 1 is a cross sectional view of my improved device, showing it as fitted upon a sound receiver and as applied to a human ear.

Fig. 2 is a front elevation of the device, 55 and

Fig. 3 is a section on the line 3—3 of Fig. 2.

In carrying out my invention I prepare a block or piece of porous or spongy material, such as spongy rubber, which has 60 a normally set structural form but is also of resilient or yieldable character so that under the application of slight pressure will yield to embed therein any object having a more rigid structure.

This block indicated in the drawing by the reference numeral 1, is there shown to have a uniform thickness of a sufficient degree to enable it to serve the purpose of my invention, which purpose is that the block 70 will contactingly overlay a human ear, and, under pressure, absorb within its yielding substance, by embedment at its surface 2, the characteristic ear features, such as the tragus, antitragus and antihelix, thereby effectually closing entrance, between the block and the ear, to the auditory canal.

The block 1 is provided with an aperture 3 that extends therethrough axially with relation to the auditory canal of the ear, 80 when applied; and this aperture, as shown, is directed toward the entrance to the auditory canal, for the better directional conveyance of sound waves toward the tympanum.

Upon the opposite, or outer surface 4 of block 1, I secure, as by cementing, or otherwise, a flexible cap or hood 5, which is provided with a central opening 6. This hood is composed of elastic material, like 90 soft rubber, to be capable of stretching so that its opening 6 may be enlarged to fit snugly over a sound receiver 7, to keep out external noises, and restrict the communication of sound to the ear solely through the 95 aperture 3.

The receiver 7 is here shown as forming part of a head piece 8 to illustrate one of the various manners in which the block 1 may be applied with pressure contactingly 100 against the ear.

Variations within the spirit and scope of my invention are equally comprehended by the foregoing disclosure.

I claim:—

1. An ear pad for sound receivers consisting of a block of resilient, porous material to lie mouldably against the ear, said block provided with an aperture therethrough for communication with the au- 110

ditory canal, and a cap of stretchable material secured to said block for removably fitting upon a sound receiver.

2. An ear pad for sound receivers consisting of resilient very soft and yielding material having a substantially flat outer face whereby said face may be pressed against the ear and the material yield to conform to and fill the convolutions of the ear, and having a sound conducting aperture for communication with the auditory canal.

3. An ear pad for sound receivers comprising a body member of resilient very

soft and yieldable material having a substantially flat outer face, whereby said face may be pressed against the ear and the material yield to conform to and fill the convolutions and irregular surface of the ear, and having a sound conducting aperture for communication with the auditory canal, and means for securing said body member to a sound receiver.

Signed at the borough of Manhattan, in the city, county and State of New York, 25 this 2nd day of August, 1922.

OSCAR BYRON. [L.S.]
